CLAIM

The ornamental design for a cable connector plug, as shown and described.

DESCRIPTION

FIG. 1 is a front, top and left perspective view of a cable connector plug showing our new design;

FIG. 2 is a rear, bottom and right perspective view thereof;

FIG. 3 is a front view thereof;

FIG. 4 is a rear view thereof;

FIG. 5 is a top plan view thereof;

FIG. 6 is a bottom plan view thereof;

FIG. 7 is a left side view thereof;

FIG. 8 is a right side view thereof;

FIG. 9 is an enlarged view of a portion indicated by 9—9 in FIG. 5; and,

FIG. 10 is an enlarged view of a portion indicated by 10—10 in FIG. 8.

The broken line showing of the environment in FIG. 3 is for illustrative purposes only and forms no part of the claimed design.

1 Claim, 3 Drawing Sheets
